BASE-BALL BAT.

1,111,314.

Specification of Letters Patent.

Patented Sept. 22, 1914.

Application filed May 14, 1913. Serial No. 767,520.

To all whom it may concern:

Be it known that I, JAMES A. MURPHY, a citizen of the United States of America, residing at Holyoke, in the county of Hampden and State of Massachusetts, have invented new and useful Improvements in Base-Ball Bats, of which the following is a specification.

This invention relates to improvements in baseball bats.

The object of the invention is to provide a bat that is designed to do away as much as possible with the "sting" when the ball strikes the extreme lower end of the bat. It is a well-known fact among baseball players that when the ball strikes the bat at certain points the vibrations imparted thereto are transmitted to the handle portion of the bat, producing what is known as the "sting" of the bat.

The present invention relates to the slitting of the lower or enlarged portion of the bat, and in addition to the slits, to the drilling of a hole axially of the bat a short distance from the extreme lower end.

Referring to the drawings,—Figure 1 is a broken plan view of the completed bat and illustrating the axially-arranged hole in the lower end of the bat and also the open-ended slits or kerfs. Fig. 2 is a transverse sectional view on the line 2—2 of Fig. 1, showing two slits in the end of the bat arranged at right-angles to each other; also showing the axially-arranged hole. Fig. 3 is an end view of Fig. 1, showing the end of the bat with only one diametrically-arranged slit or kerf.

Referring to the drawings in detail,—a designates the bat proper, the lower end of which is formed with an axially-arranged opening *b* that is drilled a suitable depth from the lower end of the bat. Extending diametrically of the end of the bat and at right-angles thereto are a pair of narrow slits or kerfs *c* and *d*. These slits, as shown, do not extend as deep as the opening *b* but terminate at the point *e*, as shown in Fig. 1.

Referring to Fig. 2, it will be seen that the grain of the wood of the bat is indicated by the wavy lines *f* and that the slits *c* and *d* are arranged so as to cut the grain of

the wood at an angle, as shown. In holding the bat the player generally turns it in his hand so that the ball, indicated in dotted lines at *g*, will engage the end of the grain of the wood and not the side of the grain, as indicated at *h*. The bat when held in this position, is prevented from being slivered; that is to say, the grain of the wood is not raised by the ball continually engaging the flat side of the grain. This position of the bat is also indicated in Fig. 3, in which the ball, indicated in dotted lines *i*, is engaging the end of the grain of wood.

Referring now to the operation of reducing the sting of vibration of the bat, it being assumed that the ball strikes one of the sectional quarters or divided end of the bat, as indicated in Fig. 2. The vibrations from the blow will be transmitted through the wood until it is prevented from traveling farther by means of the slits *c* and *d*. That is to say, the vibrations are absorbed by a portion only of the wood composing the volume of the bat, the slits serving to prevent their transmission, in a large measure, to the body and handle-portion of the bat, thus reducing the effect of the "sting," as has been proved by actual experiments.

In Fig. 3, in which only one slit *j* is shown, the ball would transmit to the segment *k* the vibrations from the blow, which vibrations would travel through the wood until it is intercepted by the diametrically-arranged slit *j* and thus prevented from transmitting such vibrations to the body of the bat. It will be noticed that the extreme end portions of the slits are slightly rounded, as indicated at *m*. This is for the purpose of preventing the cover of the ball being torn should it accidentally engage the edge portions of the slits.

The handle portion of the bat as shown is provided with a cord wound thereon but does not form any part of the present invention.

While I have shown in Figs. 1, 3, and 5 and set forth in the specification the manner of applying a cord to the handle portion of the bat in order to assist the batter or user to obtain a better grip, I do not, however, make any claim to such feature of my invention as base-ball bats with a wound han-

dle are already known to the public, a good example of which is shown in Letters Patent of the United States, granted to L. S. May, on June 3, 1913 and numbered 5 1,063,563.

What I claim, is,—

1. A baseball bat designed to lessen the effect of "sting" and having its extreme ball-engaging end formed with an axially-arranged opening, a diametrically-arranged slit or kerf intersecting the opening and terminating in the sides of the bat; said slit being of less depth than the depth of the opening, and arranged at an angle to the grain of the wood, whereby the vibrations imparted to a segmental portion of the bat when the ball is struck will be intercepted by the slit and prevented from

being transmitted through the body of the bat to the handle-portion, as described. 20

2. In a baseball bat, the lower end of which is formed with an axially-arranged opening and one or more diametrically-arranged slits intersecting the opening and terminating in the sides of the bat, the edge 25 portions of the slits being rounded to prevent tearing the cover of the ball when the same engages this portion of the slits and whereby said slits are designed and arranged to prevent the transmission of the 30 vibrations through the bat when the ball is struck, as described.

JAMES A. MURPHY.
